FILLING END PARTING AND CLAMPING MECHANISM

Edward C. Nichols, Upton, Mass., assignor to Draper Corporation, Hopedale, Mass., a corporation of Maine

Application June 19, 1940, Serial No. 341,330

7 Claims. (Cl. 139—263)

The present invention pertains to automatic filling replenishing looms and has more particular reference to filling end parting and clamping mechanism for such looms.

5 The operation of the filling replenishing mechanism of the conventional automatic loom results in the formation of a length of filling, called an outgoing filling end, which extends from the cloth selvage to the outgoing filling carrier. The 10 outgoing filling end, particularly in bobbin changing looms, must be severed at a point between the cloth selvage and the filling carrier at about the same time the filling carrier is ejected from the loom. Preferably, the part or branch of such 15 filling end which extends from the selvage to the point of severing is clamped and withdrawn out of range of the weaving instrumentalities. There is accordingly provided in such looms a movable carrier having parting and clamping 20 blades thereon, the carrier and blades being usually manipulated so as to part and clamp the outgoing filling end and withdraw it out of range of the weaving instrumentalities simultaneously with the transferring operation. In looms of the 25 type above referred to the carrier is usually slidably mounted in a guide and reciprocated therein toward and from the shuttle box. In such constructions the guide is usually mounted so that the path of reciprocation of the carriage is 30 inclined to or at an acute angle with the longitudinal center line of the lay. By having the carriage and parting and clamping blades reciprocate along a path inclined to or at an acute angle with the longitudinal center line of the 35 lay, the parting and clamping blades are closer to the cloth selvage at the forward end of their stroke than at the rearward end thereof. This is done to prevent stretching of the outgoing filling end as it is withdrawn forwardly from the 40 shuttle box after being severed.

By withdrawing the spent filling end from the shuttle in the manner above described and moving the clamped end towards the cloth selvage, slack is produced in the outgoing filling end 45 which facilitates its passage through the longitudinal slot in the front box plate, and in addition such withdrawal prevents undue tension being placed on the outgoing filling end which tension may result in a shiner in the cloth or in 50 the breakage of the filling end between the clamping blades and the cloth selvage thereby leaving a free end which may be caught in the shed producing a defect in the cloth. However, the angle or inclination, between the path of reciprocation of the carriage and the longitudinal 55

center line of the lay, which will produce the proper slack in the outgoing filling end varies according to the particular type of cloth being woven, the particular type of thread used and the variation in the beat of the cloth. 5

Accordingly it is the principal object of the present invention to provide an automatic filling replenishing loom having bobbin transferring mechanism, a lay having a shuttle box thereon, a carrier having parting and clamping 10 blades mounted thereon and movable towards and from the shuttle box, a guide in which the carrier moves, a bracket for supporting the guide, comprising two members adjustable about a vertical axis whereby the angle between the 15 path of reciprocation of the carriage and the longitudinal center line of the lay may be adjusted to provide the proper slack in the outgoing filling end upon withdrawal of such end from the shuttle box after being severed. 20

The foregoing and other objects of the invention are accomplished by the construction illustrated on the accompanying drawing, of which:

Fig. 1 is a perspective view of the parting and clamping mechanism showing the preferred embodiment of my invention applied thereto; and 25

Fig. 2 is a perspective view to a large scale of the two-piece mounting bracket shown on Fig. 1. 30

The loom to which my invention has been applied is but partially shown on the drawings, the parts omitted being of conventional construction and not of the present invention. 35

There is shown a part of a right hand loom side 1 carrying a rotary hopper 2, and part of the bobbin transferred mechanism including a transfer hammer 3 mounted on a stub shaft 4 in the hopper. 40

The lay 5 reciprocates forwardly and rearwardly in the usual manner and is provided with a shuttle box 6 for receiving a shuttle 7. Operation of the transferring mechanism results in the formation of the out-going filling end which must be parted somewhere close to the shuttle box and one branch clamped and withdrawn 45 from the path of the lay and shuttle box.

The parting and clamping mechanism shown may be supported from the stub shaft 4 by means of a bracket adjustably mounted thereon. Such bracket may include an upper member 8 and a 50 lower member 9. The member 8 is adjustably mounted on stub shaft 4 by means of set screw 10 and has a hole 11 adjacent its rear end and an arcuate slot 12 adjacent its forward end. Member 9 is pivotally connected to member 8 55

by means of a bolt 13 passing through hole 11 in member 8 and hole 14 in member 9.

Angular adjustment of member 9 in relation to member 8 about a vertical axis is provided by means of a bolt 15 passing through slot 12 in member 8 and a hole 16 in member 9. Member 9 has a pair of depending lugs 17 and 18. Each of lugs 17 and 18 is provided with an elongated vertical slot 19 and 20 respectively. A guide 21 is vertically adjustably secured to member 9 by means of bolts 22 and 23 received in slots 19 and 20 respectively. A carrier 24 is slidably mounted in the guide 21 for movement forwardly and rearwardly of the loom. A movable parting blade 25 and a movable clamping blade 26 are pivotally mounted on the carrier 24. These blades cooperate with blades 27 and 28 which are fixed to the carrier.

The carrier and the parting and clamping blades are thus mounted in front of the shuttle box. They are moved to filling receiving position, i. e., rearwardly toward the shuttle box, prior to each transferring operation and are withdrawn forwardly from such position simultaneously with the transferring operation.

To this end a bracket member 29 is pivotally suspended from the stub shaft 4. Adjustably connected to bracket member 29 is another bracket member 30. Bracket member 30 has one end turned downwardly and this end has an elongated slot 31 therein for the reception of a pin (not visible on the drawing) projecting from the carrier 24. Bracket member 29 has a downwardly turned end having an adjustable connection 32 with a lever 33, the lever 33 may be connected to and actuated by the latch depressor, not shown. Thus on the rearward movement of the latch depressor, the brackets 29 and 30, and through the pin and slot connection, the carrier 40 24, are moved rearwardly toward the shuttle box.

Simultaneously with the transferring operation the lay (or parts thereon) will strike screw 34 on the carrier, thus withdrawing or returning the carrier forwardly.

Means are provided for opening and closing the parting and clamping blades. Such means may comprise a cam 35 carried by a bracket 36 mounted on guide 21 by means of bolt 37. Cam 35 engages a pin 38 projecting from the movable blade 26 to move the blades to open position. A second cam mechanism 39 operates to close the blades after they have been properly positioned to sever the outgoing filling.

When cloth of a different type is to be woven or a change is made in type of yarn such as from cotton to rayon, there will be a variation in the beat of the cloth, this variation if uncompensated for may produce a tension on the last pick laid just before transfer, when the outgoing filling end is withdrawn from the shuttle. To compensate for this variation in the beat of the cloth it is only necessary to loosen bolts 13 and 15 and adjust the member 8 in angular horizontal relation to member 9 to change the angle 65 of the path of reciprocation of the carrier 24 thereby compensating for the change in the variation of the beat of the cloth.

Having thus described the preferred embodiment of my invention, I claim:

1. In an automatic replenishing loom, the combination of a lay having a shuttle box thereon, filling end parting and clamping mechanism including a carrier having parting and clamping blades mounted thereon, said carrier being adapted to reciprocate forwardly toward and

rearwardly from the shuttle box, a support for supporting said parting and clamping mechanism in front of said shuttle box, and means adjustably connecting said parting and clamping mechanism to said support for movement in relation thereto about a vertical axis whereby the angle which the path of reciprocation of said carrier makes with the longitudinal center line of the lay is adjustable.

2. In an automatic replenishing loom, the combination of a lay having a shuttle box thereon, an adjustable support including a fixed member located in front of the shuttle box and connected to a stationary part of the loom, a movable member connected to said fixed member and adjustable in relation thereto about a vertical axis and a parting and clamping mechanism including a carrier having parting and clamping blades mounted thereon, means for moving said carrier toward and from said shuttle box in a substantially horizontal plane, a guide in which said carrier reciprocates, said guide being attached to said movable member, whereby the angle which the path of reciprocation of the carrier makes with the center line of the lay is adjustable.

3. In an automatic replenishing loom, the combination of a lay having a shuttle box thereon, an adjustable support located in front of said shuttle box, said support comprising a fixed member connected to a stationary part of the loom, a movable member pivotally connected to said fixed member adjacent one end thereof and adjustable in relation thereto about a vertical axis and means for clamping said members in adjusted position, and a parting and clamping mechanism including a carrier having parting and clamping blades mounted thereon, means for moving said carrier forwardly towards and rearwardly from the shuttle box and actuating said blades, and a guide in which said carrier reciprocates, said guide being connected to said movable member; whereby the angle which the path of reciprocation of the carrier makes with the center line of the lay is adjustable.

4. In an automatic replenishing loom, the combination of a lay having a shuttle box thereon, an adjustable support located in front of said shuttle box and including a bracket adjustably attached to a stationary part of the loom, a movable member pivotally connected to said bracket at one end and having a slot and bolt connection to said bracket at the other end whereby said movable member is adjustable in relation to said bracket about a vertical axis and a parting and clamping mechanism including a carrier having parting and clamping blades mounted thereon, means for moving said carrier towards and from the shuttle box in a substantially horizontal plane, a guide in which said carrier reciprocates, said guide being attached to said movable member; whereby the angle which the path of reciprocation of the carrier makes with the center line of the lay is adjustable.

5. In a filling end parting and clamping mechanism for filling replenishing looms having a lay and a shuttle box thereon, the combination of a reciprocatory carrier having parting and clamping blades mounted thereon, said carrier being adapted to reciprocate in a substantially horizontal plane towards and from the shuttle box, a guide in which said carrier reciprocates, a support for supporting said guide in front of said shuttle box, and means adjustably connecting said guide to said support for movement in

relation thereto about a vertical axis whereby the angle which the path of reciprocation of the carrier makes with the center line of the lay is adjustable.

- 5 6. In a filling end parting and clamping mechanism for filling replenishing looms having a lay and a shuttle box thereon, the combination of a reciprocatory carrier having parting and clamping blades mounted thereon, means for reciprocating said carrier towards and from the shuttle box in a substantially horizontal plane, a guide in which said carrier reciprocates and a support for supporting said guide in front of the shuttle box, said support comprising a bracket adapted to be connected to a stationary part of the loom, a movable member pivotally connected to said bracket at one end and having a slot and bolt connection therewith at the other end whereby said member is adjustable in relation to said bracket
- 10 15
- 20 about a vertical axis, said guide being attached to said movable member; whereby the angle which

the path of reciprocation of the carrier makes with the center line of the lay is adjustable.

7. In an automatic replenishing loom, the combination of a lay having a shuttle box thereon, filling end parting and clamping mechanism including a carrier having parting and clamping blades mounted thereon, means for reciprocating said carrier towards and from the shuttle box in a substantially horizontal plane, a guide in which said carrier reciprocates and an adjustable support including a bracket attached to a stationary part of the loom, a movable member pivotally connected to said bracket at one end and adjustably connected to said bracket at the other end for movement in relation to said bracket in a horizontal plane about said pivotal connection, said guide being connected to said movable member; whereby the angle which the path of reciprocation of the carrier makes with the lay is adjustable.

EDWARD C. NICHOLS.
